DES. 1971

Isaac S. Clough, of Brooklyn, N.Y. and

Vincent Fountain, of Castleton, N.Y.

Letter Patent No. 1971-Dated July 19, 1861

Design for a Lantern.

The schedule referred to in these Letters Patent and making part of the same.

Isaac S. Clough, of Brooklyn, N.Y.

Be it known that we, Isaac S. Clough, of Brooklyn, in the County of Kings and State of New York, and Vincent Fountain, of Castleton, in the County of Richmond and State of New York, have invented a new Design for a Lantern; and we do hereby declare that the following is a full, clear and exact description of the same, reference being had to the accompanying drawings forming part of this specification in which

Figure 1 is an elevation of one side of the lantern.

Figure 2 is a horizontal section of the lantern.

Figure 3 is a longitudinal section of the lantern.

This lantern is three-sided as shown by the horizontal section Fig. 2, and has its top of an ogee form, as represented in Figures 1 and 3.

One side, shown in Fig. 1, is represented a medallion for the reception of any portrait, the said medallion being surrounded by a blue ground, on which are white stars, &c., or in other words the side may be said to have represented upon it the "Union" of the American Flag, with a medallion in, or nearly in the centre.

On the other two sides there are alternately red and white horizontal stripes, as shown in Fig. 3, representing the field of the flag.

DES. 1971

2

The three sides of the lantern combined are thus made to show
the American Flag with a medallion upon its union.

What we claim as our invention, and desire to secure by Letters

Patents -

The design for a three-sided lantern, herein described and
represented in the accompanying drawings.

Witness,

Henry E. Brown
